G. W. Randall.

UNITED STATES PATENT OFFICE.

GEORGE W. RANDALL, OF BOSTON, MASSACHUSETTS, ASSIGNOR TO HIMSELF AND REUBEN I. TODD, OF SAME PLACE.

FAUCET.

Specification of Letters Patent No. 23,533, dated April 5, 1859.

To all whom it may concern:

Be it known that I, GEORGE W. RANDALL, of Boston, in the county of Suffolk and State of Massachusetts, have invented a new and useful Faucet or Hydrant, which I term the "Duplex Faucet"; and I do hereby declare that the same is fully described and represented in the following specification and the accompanying drawings, of which—

10 Figure 1, denotes a front elevation of it. Fig. 2, a vertical section of it. Fig. 3, a horizontal section taken through the series of induction pipes. Fig. 4, is a top view of it.

15 The nature of my invention consists of a combination of two taps or valve tubes and a case or body provided with two or more conduit pipes, the whole being arranged, constructed and applied together in such manner 20 as to enable either of the currents of fluid conducted into the case by either of its conduits to be discharged out of the lower end of the inner tap or valve tube and the remainder of the currents to be shut off therefrom. Or 25 my said invention may be used for the purpose of leading a current of a fluid into any one of a series of conduits at pleasure or as circumstances may require.

30 In the drawings, A, represents the case or body part of the duplex faucet, while B, and C, are the valve tubes or taps. The outermost tap, B, not only receives the inner tap C, but is received by the case in like manner or as the tubular valve induction pipe of a 35 common faucet enters and works in the body or induction part of such a faucet. The case or body A, is provided with two or more radial conduits or pipes D, D, D, D, which open into the tap hole, E, E, thereof, 40 as shown in Fig. 3.

45 The tap, B, is tubular and ground to fit and turn in the hole E, E, with a water tight joint and it has an inlet hole a, made horizontally through it and with its center in the plane of the axes of the conduits, as shown in Figs. 2, and 3. Furthermore, the tap B, may be furnished with a series of radial arms b, b, b, &c., extending from it as seen in the drawings such being for the purpose of enabling a person to revolve the tap 50 within the case A, so as to bring the inlet hole of the tap in a line with any one of the conduits D, D, D.

55 The inner tap is open at bottom and closed at top. It extends through the outer tap and should be ground to fit it so as to turn

on it with a water tight joint. A hole or passageway c, should be made through the side of the inner tap C, in the same plane with the axes of the conduits as seen in Figs. 60 2, and 3.

The head or that part d, of the tap C, which extends above the tap B, may be milled as shown at e, e, in Fig. 1, or it may be provided with any other suitable means 65 by which the tap may be easily turned around axially within the outer tap as that is capable of being turned within the case A.

A long notch f, made in the upper part of the tap B, (as shown in Fig. 1,) serves in 70 connection with a pin g, extending from the inner tap C, to determine the extent of rotary movement of the inner tap, the inlet passage of the tap C, being brought into line with that of the tap B, when the stud is 75 against one end of the notch. By moving the inner tap so as to carry the inlet orifice thereof beyond that of the outer tap, the latter orifice will be closed. By means of the auxiliary or inner tap combined with the 80 outer tap as described, a fluid may be drawn from either of the conduits and the change made from one to the other without any draft from any of those which may be intermediate.

85

With but one tap and a case provided with a series of conduits, it will readily be seen that whenever it might be desirable to draw a liquid from a conduit, such conduit might be so situated that in order to bring it 90 into line with it, the inlet orifice of the tap, such orifice would have to pass across some one or more of the other conduits, in which case, some of the liquid from them would be likely to flow into it and run out of the 95 discharge end of the tap. Now, the auxiliary tap enables us to shut the inlet orifice of the outer tap and keep it shut while it may be in the process of being moved from one of the conduits to any other of the series. After the change may have been made 100 the inner tap may be turned so as to carry its inlet orifice into line with that of the other tap, in which case, the liquid will flow directly into the inner tap and be discharged 105 from its lower end.

My invention is particularly calculated for drawing ale or spirits or liquors of various kinds from sundry reservoirs and through one discharge tube or tap.

110

In order that the fluid which may enter the inner tap may be discharged therefrom

or not hindered by atmospheric pressure from free flowage from it I provide the inner tap with an air passage, *p*, to extend vertically upward from the lower end of the 5 tap and alongside of the bore of the same and to open into the inlet orifice of the said tap. As air can flow through this passage upward into the bore of the inner tap, the pressure of the atmosphere cannot operate toward retaining any of the fluid in 10 the tap. The arrangement of the said air passage is such that, should any liquid be discharged by it, it will pass downward with or close to the stream that may flow 15 out of the tap. Were the said air passage made through the top part of the tap it would operate to let air into the top, but at the same time, more or less liquid would be likely to be discharged from it, in a 20 wrong or inconvenient direction. The peculiar arrangement of the air passage with respect to the bore of the tap or so as to open out of the lower end of the tap, or discharge liquid downward is an improvement 25 and productive of a useful result, as by

means of it, the liquid that may be discharged from the tap and air passage may be received into the same vessel.

There may be an index on the outer surface of the outer tap. Also, a series of such 30 marks or divisions on the outer surface of the case A, as will enable a person with such index to stop the inlet orifice of the tap against any one of the conduits of the case.

What I claim is—

1. The combination of the auxiliary or inner tap with the outer tap and the conduit case, provided with two or more conduits, the whole being constructed and made to operate together substantially as specified. 35 10

2. I also claim the arrangement of the air passage, *p*, so as to discharge with reference to the discharging end of the inner tap substantially as described.

In testimony whereof, I have hereunto 45 set my signature.

GEO. W. RANDALL.
